BRASSIÈRE

William Rosenthal, New York, N. Y., assignor to
Maiden Form Brassière Co. Inc., New York,
N. Y., a corporation of New York

Application April 1, 1932, Serial No. 602,586

3 Claims. (Cl. 128—280)

This invention relates broadly to a new brassière construction.

One of the objects of this invention is the provision of a brassière which is adapted to support the bust in a natural position.

A further object of this invention is the provision of a brassière formed with pockets of novel construction which are attached to the backbands without Shirring.

10 A further object of this invention is the provision of a novel brassière construction which includes a plurality of elastic inserts interposed in the waist band portion thereof, so as to make it mold to the body of the wearer and lessen the strain of the brassière.

A still further object of this invention is the construction of a brassière having breast receiving pockets therein constructed of novel, irregular shaped pieces to provide an arrangement without Shirring.

20 A still further object of this invention is the construction of a brassière incorporating novel features which render it peculiarly adaptable for use as a nursing brassière, a goodly portion 25 of the front of which may be opened without taking off the brassière from the wearer's body.

A still further object of this invention is the construction of a brassière including separable means whereby the pockets thereof may be 30 opened along the line of joinder thereof.

A still further object of this invention is the construction of a brassière including novel pocket lining members.

35 A still further object of this invention is the provision of a novel brassière construction, wherein the shoulder straps may be adjusted or opened by buttoning.

40 A still further object of this invention is the provision of a brassière formed with pockets attached along their lower edges to a waist band.

45 A still further object of this invention is the provision of a brassière incorporating novel features of pocket construction, pocket lining members, adjustable shoulder bands, and means for opening and separating the pockets at the front thereof so that the brassière may be used to advantage as a nursing brassière which may be opened without removing the brassière from the wearer's body.

50 These and many other objects are secured by the brassière construction herein disclosed.

This invention resides substantially in the combination, construction, arrangement and relative location of parts, all as will appear more fully hereinafter.

Referring to the drawings in which the same reference numerals will be used throughout the several views to indicate the same or similar parts—

Figure 1 represents a front perspective view 60 of a brassière employing the novel principles of my construction;

Fig. 2 represents a rear perspective view thereof;

Figs. 3 and 4 represent a portion of the elements which form the back band;

Figs. 5 and 6 represent pieces which form portions of the pockets;

Figs. 7 and 8 represent pieces which form the 70 remaining portions of the pockets;

Fig. 9 represents the band, along the upper edge of which the respective pockets are secured;

Figs. 10 and 11 represent elastic inserts for 75 yieldingly securing said band to the back band portions;

Fig. 12 represents the outer pocket lining member;

Fig. 13 represents the inner pocket lining 80 member;

Fig. 14 represents a rear elevational view of the brassière undone and spread out;

Fig. 15 represents a front elevational view of the brassière as worn but shown with one pocket thereof in opened position.

85 Considerable difficulty has been encountered heretofore in creating a convenient and comfortable nursing brassière which may be readily opened while nursing and which, due to its construction, will firmly and securely support the breasts without irritation of the wearer's skin.

As a matter of fact, as is commonly known, brassières have not generally been worn by women while nursing, due to a lack in the prior art of any moisture-proof breast confining construction, which could be readily opened.

90 It is the purpose of this invention, therefore, to provide a novel type of brassière of novel pocket construction which may be readily opened and which includes moisture-proof breast confining elements which operate when the brassière is worn to prevent breast exudations from

95 contacting with and soiling either the brassière pockets or other garments that are worn. The breast confining elements, as will be disclosed, while necessarily moisture-proof must, on their inner surface, be of soft material and without raised seams or of other irritation producing construction.

100 Referring now to the drawings, it will be noted 110

that I have shown at 1 a body band with elastic inserts 2 and 3 secured thereto. Secured to these elastic inserts are the portions 4 and 5 which comprise portions of the back-band. The portions 4 and 5, as shown in Figs. 3 and 4, are provided with cuts 6 and 7, the edges of which are drawn together and stitched so as to produce a curved effect in the resulting back-bands. Interposed in a cut in the band 1 is an elastic element 8 which is secured thereto by stitching and renders the upper portion of the body band yieldable at the middle front portion thereof. Secured to the upper edge of the band 1 are the two pockets 9 and 10, each of which is formed of two elements 11, 11' and 12, 12' shown in Figs. 5 to 8 inclusive.

It will be apparent from the foregoing that by stitching the elements 11 and 12 together a pocket is readily created in which the irregular shaped members shown are readily secured together along two seams emanating from a single point, by means whereof a convenient pocket is formed involving but a minimum of seaming. Disposed along the free edge of pocket 9 are shown a plurality of hooks 13 adapted to cooperate and engage with a plurality of eyes 14 disposed along the free edge of pocket 10. As is obvious, these hooks and eyes when secured together make it possible for the pockets to be firmly engaged one with the other to present a closed front. When the hooks are disengaged from the eyes, the front of the brassière may be rapidly and conveniently opened.

Attached to the upper edge of each of the pockets are buttons 15 and 15', which are adapted to cooperate with button-holes 16 and 16' in the shoulder bands 17 and 17'. These shoulder bands at their free ends are secured to the back-bands 4 and 5 by elastic members 18 and 18'. The back-bands 4 and 5 may be joined together by the conventional hook and eye strap 19.

Turning next to the inside of the pockets, it will be noted from Fig. 2 that a piece of netting 20 may be provided to cover over the seaming occasioned by the securing of pocket elements 11, 11' to pocket elements 12, 12'. Secured to the pockets along the lower edge thereof and along the upper edge of the front band 1 are the lining elements generally indicated by 21, 21'. These lining elements are formed so as to be moisture-proof, yet of non-irritating qualities where they contact with the wearer's skin. As shown, they consist in an outer lining pocket 24 of rubberized fabric or the like which is folded along the lines 25 to yield the conformed moisture-proof exterior of the pocket lining members 21, 21'. Secured to the inner surface of each of the rubberized pocket linings 24 are the absorbent linings 22 of flannel or the like, which is cut along the lines 23 and stitched along the lines 23^a to conform the same to the rubberized lining pocket member without seaming along a line of cut.

It will be apparent from the foregoing that while the absorbent sheeting which comprises the element 22 may be cut and seamed together along the line 23^a, that to prevent all leakage no cut should be or is provided in the rubber sheeting comprising the element 24. Rather, the outer water-proof lining is formed into pocket shape by folding an uncut portion of rubberized fabric or the like as above set out.

Secured to the flannel 22 of each pocket along the inner surface thereof are the two supporting

straps 26, which are adapted to support an absorbent gauze dressing or the like 29 (Fig. 14), which may be employed to take up exudated milk or the like when the absorbent qualities of the flannel do not suffice the wearer's needs. The outer rubberized pocket lining 24 and the inner flannel lining 22 are secured together along the free edges thereof by a tape binding 27 to present a smooth edge. Along the lower inner edge of the pocket lining members 21, 21', where they join the band 1, a flannel ridge 28 is provided which, in conjunction with the pocket lining elements 21, 21', tends to absorb the moisture and keep it from escaping onto and dampening the band 1 or other garments which may be worn. In effect, the flannel ridge 28 acts as a confining and moisture absorbing member for the lower surface of the breast.

As will be apparent from the foregoing, to use the brassière I have invented, the hook and eye strips 13 and 14 of the respective pockets are closed, the lining pocket members are pushed forward in pocket formation and the brassière put on in the usual fashion by securing the back-bands together by the hook and eye strip 100

19. The shoulder straps 17 are then adjusted by buttoning the buttons 15, 15' into convenient button holes 16, 16' and the excess free ends of the shoulder bands 17 are then slipped between 105 the pockets 9, 10 and the lining pocket elements 22, 22'.

If and when desired, any individual pocket may then be opened by undoing the hook and eye strip 13, 14, either for nursing or for the insertion of a dressing, under the straps 26. If desired, the whole front of either or both pockets 9, 10 may be released by unbuttoning the buttons 15, 15', as well as by undoing the hook and eye strip 13, 14. When this is done the elastic element 8, as will be obvious, permits of ready and easy folding down or removal to one side of the whole breast supporting pockets and exposure of the breast, or breasts, all without removing the brassière from the wearer's body.

It will be obvious from the foregoing that the brassière construction which I have disclosed incorporates many features which are possible of general adaptation in brassières other than nursing brassières. For instance, the pocket construction disclosed in connection with the pockets 9 and 10 may, obviously, be conveniently and valuable employed in connection with all types of brassières. Moreover, the construction herein disclosed might be satisfactorily and successfully employed in devices to be worn when surgical treatment of the breast is necessary at repeated intervals, such as repeated dressings in the case of wounds or the like.

I am, of course, aware that many changes in the detail of construction and relative arrangement of parts may readily suggest themselves to those skilled in the art and I do not, therefore, desire to be limited to the exact details disclosed by the way of illustration, but rather to the spirit and scope of my invention as I define it in the appended claims.

What I seek to secure by United States Letters Patent is:

1. As a new article of manufacture, a freely movable pocket lining member adapted to securement only to the lower edge of a brassière pocket and comprising an outer moisture-proof pocket liner, and an inner absorbent lining sheet

- secured directly together over the whole of the edges thereof.
2. In a brassière construction, a plurality of breast receiving pockets, a freely movable moisture-proof lining member secured to each pocket only along its lower inner edge, a back band secured to the free end of each pocket, and means for detachably securing said back bands together.
- 10 3. In a brassière construction of the type de-

scribed, a plurality of breast receiving pockets united along their lower edges to a band, a freely movable moisture-proof lining element secured to each pocket only along its lower edge, and which element is therefore adapted to ready uncovering of the wearer's breast, back bands secured to the free ends of said pockets, and means for detachably securing said back bands together.
